Patented Nov. 25, 1975

237,827

COIL-WINDING MACHINE

Lincoln Rogers, Caledonia, N.Y., assignor to
Coil-Ler Manufacturing Co.

Filed Mar. 13, 1973, Ser. No. 340,817

Term of patent 14 years

Int. Cl. D15—99

U.S. Cl. D54—14 R

FIG. 1.

FIG. 2.

Fig. 3.

FIG. 5.

FIG. 4.

FIG. 1 is a side elevation of a coil-winding machine, showing my new design, looking at one side of the machine;

FIG. 2 is a side elevational view, looking at the opposite side of the machine;

FIG. 3 is a plan view thereof;

FIG. 4 is an end view, looking at the right end in FIG. 2; and

FIG. 5 is an end view, looking at the left-hand end in FIG. 2.

I claim:

The ornamental design for a coil-winding machine, substantially as shown.
